UNITED STATES PATENT OFFICE.

WILLIAM HENRY BARR, OF STEUBENVILLE, OHIO, ASSIGNOR TO ALEXANDER J. BEATTY & SONS, OF SAME PLACE.

DESIGN FOR A JAR.

SPECIFICATION forming part of Design No. 18,223, dated April 3, 1888.

Application filed January 11, 1888. Serial No. 260,452. Term of patent 3½ years.

To all whom it may concern:

Be it known that I, WILLIAM HENRY BARR, a citizen of the United States, residing at Steubenville, in the county of Jefferson and State of Ohio, have invented and produced a new and original Design for Glassware; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This description relates to the ornamentation of glassware, chiefly such as is designed for table use.

The leading feature of the design is parallel bars or ribs integral with the body of the article. These ribs or bars extend from the top of the article to or beneath the bottom thereof, and terminate in radial lines, which vanish as they approach the center of the bottom, and are of any contrasting color with the body of the ware.

In the drawings, Figure 1 is a side view of a jar embellished with my design; Fig. 2, a bottom plan view, and Fig. 3 a transverse section on the line X X of Fig. 2 of the jar.

The jar A and the ribs or bars B, of contrasting color, are integral, and the ribs extend flush from the top of the jar to the bottom thereof in straight parallel lines, and project beneath said bottom in converging lines, which vanish as they approach a central point. The ribs stand out boldly from the jar and have well-defined channels between each two, the channels being about equal in cross-sectional area to a cross-section of the rib.

Having thus described my invention, what I claim, and desire to secure by Letters Patent, is—

The herein shown and described design for a jar or similar article of glassware, consisting of straight parallel ribs or bars of contrasting color with the body of the jar, and extending from the top to the bottom of the jar, and having well-defined grooves or channels between each two of the bars, the channel being about equal in cross-sectional area to a cross-section of a bar.

In testimony whereof I affix my signature in presence of two witnesses.

WILLIAM HENRY BARR.

Witnesses:

GEORGE BEATTY,
P. E. BRADY.
